CLAIM

The ornamental design for a holder for microphone, as shown and described.

DESCRIPTION

FIG. 1 is a front and top perspective view of a holder for microphone, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion of the holder for microphone labeled, '9' in FIG. 1;

FIG. 10 is an enlarged view of a portion of the holder for microphone labeled, '10' in FIG. 1.

FIG. 11 is an enlarged view of a portion of the holder for microphone labeled '11' in FIG. 1;

FIG. 12 is an enlarged view of a portion of the holder for microphone labeled '12' in FIG. 1;

FIG. 13 is an enlarged view of a portion of the holder for microphone labeled '13' in FIG. 6;

FIG. 14 is an enlarged view of a portion of the holder for microphone labeled '14' in FIG. 6; and,

FIG. 15 is an enlarged view of a portion of the holder for microphone labeled '15' in FIG. 6.

The broken lines in the figures illustrate portions of the holder for microphone that form no part of the claimed design. The dash dot dash broken lines shown in FIGS. 1, 6 and 9-15 encircling portions of the holder for microphone illustrated in enlargements form no part of the claimed design.

1 Claim, 15 Drawing Sheets
